N° 824.

N. S. Geddes
Assign to Cox, Richardson & Boynton.
Design for Coal Stove.

Patented Aug. 19. 1856.

Des. 824

N. S. Wedder of Troy, New York, -

assignee to

Boy, Richardson & Boynton, of the same place.

Letter Patent, No. 824. Dated Augt 19th 1856.

The schedule referred to in these Letters Patent, and making part of the same.

To all whom it may concern:

Be it known that I, N. S. Wedder, of Troy, in the County of Rensselaer and State of New York, have invented or produced a new and original design, for an elevated Oven Cook Stove, which I call the "Live Oak", and I do hereby declare that the following is a full, clear, and exact description of the same, reference being had to the annexed perspective drawing, forming part of this specification.

My design for an elevated oven cook stove, is as follows, viz; A, is the top plate with the moulding (a). B, is the front plate, with fire doors C, C, having upon them panels the ornaments (b, b,) the mouldings (c, c,) form the door frame. D, is the jambs plate, with fire doors E, and E', with panel ornaments (d,) and (e). G, is the bottom plate with ornamental moulding (f). H, is the leg with ornament (g) upon its face. I, is the front plate of the elevated oven, having the ornamental moulding (h) and ornaments (i) and corner rosette (j). J, is the end plate with the moulding (k) and oven door K, with the panel ornament (l). L, is the top plate of the oven.

Having fully described my design for an elevated oven cook stove, what I claim as new and desire to secure by Letters Patent, is, The ornamental design and configuration of Cook Stove plates, such as herein described and shown in the annexed perspective drawing.

Witness,

J. J. Savage }
John Moran }

N. S. Wedder
